UNITED STATES PATENT OFFICE.

FRANKLIN E. ARNDT, OF GALION, OHIO, ASSIGNOR OF ONE-HALF TO DAVID C. BOYD,
OF GALION, OHIO.

INTAKE-MANIFOLD.

1,278,558.

Specification of Letters Patent. Patented Sept. 10, 1918.

Application filed January 12, 1918. Serial No. 211,600.

To all whom it may concern:

Be it known that I, FRANKLIN E. ARNDT, a citizen of the United States, residing at Galion, in the county of Crawford and State 5 of Ohio, have invented certain new and useful Improvements in Intake-Manifolds, of which the following is a specification.

This invention relates to an improved intake manifold for motor vehicle engines and 10 has for its primary object to provide an intake manifold especially designed for use in connection with an engine of the type used in the Ford automobile, and which is intended to be substituted for the intake manifold 15 of the engine and interposed between the usual exhaust manifold and the ports of the engine cylinders.

In its broadest aspect, the invention contemplates the provision of a simple and effective manifold construction which will 20 result in the thorough vaporization of relatively low grade hydrocarbon fuels, such as kerosene and the like, and which will also increase the vaporization of gasoline or 25 other relatively refined fuels in the passage of such fuel from the carburetor to the cylinder intake ports, to the end that a maximum of completely vaporized gas will be obtained and the ultimate degree of power efficiency 30 procured in the combustion thereof.

It is another object of my invention to provide an intake manifold wherein the gaseous mixture is heated and thoroughly vaporized by the exhaust from the engine 35 cylinders, the manifold being so constructed that it may be readily applied in operative position with relation to the exhaust manifold, without necessitating structural changes of any character whatever in the latter.

40 The invention also has for one of its more specific objects to provide an intake manifold as above characterized having spaced exhaust receiving ports and intake ports spaced from the exhaust ports, and means 45 for directing the gaseous mixture in close confinement around the walls of the exhaust ports, whereby the mixture is heated to a very high degree and all solid particles of fuel thoroughly vaporized in the passage of 50 such mixture to the intake ports.

It is likewise one of the secondary objects of my invention to provide a manifold construction wherein the incoming gaseous mixture is equally divided in the manifold and 55 distributed in uniform volume to the re-

spective intake ports without creating back pressure through the carburetor connection.

And it is a further general object of my invention to provide a hydrocarbon fuel vaporizer embodied in the construction of 60 the intake manifold, which is relatively simple, as well as highly effective and reliable in practical use, may be easily and quickly applied in operative position without requiring the services of a skilled mechanic, and 65 by the use of which appreciable economy may be realized in the operation of the engine.

With the above and other objects in view, my invention consists in the novel features 70 of construction, combination, and arrangement of parts to be hereinafter more fully described, claimed and illustrated in the accompanying drawings, in which:

Figure 1 is an elevation partly in section 75 showing my improved intake manifold applied to a motor vehicle engine of the Ford type in conjunction with the usual exhaust manifold;

Fig. 2 is a top plan view; 80
Fig. 3 is a rear side elevation of the intake manifold;

Fig. 4 is a horizontal section taken on the line 4—4 of Fig. 1;

Fig. 5 is a section taken on the line 5—5 85 of Fig. 1;

Fig. 6 is a section taken on the line 6—6 of Fig. 1; and

Fig. 7 is a section taken on the line 7—7 90 of Fig. 1.

Referring in detail to the drawing, 5 designates the front side or body wall of the vaporizer casing and 6 and 7 respectively indicate the longitudinally extending top and bottom walls thereof. These top and bottom walls preferably converge longitudinally to the ends of the manifold and are integrally connected by the terminal exhaust ports 8. The top wall 6 at the center of the manifold and at each side thereof is downwardly curved, as shown at 9. 10 designates the curved goose-neck connection to the carburetor (not shown) which is integrally formed with the bottom wall 7 of the manifold at its longitudinal center. 100

The bottom wall 7 extends in a horizontal plane for a short distance upon each side of the carburetor connection 10 and at the ends of such horizontal portions of the wall 7, vertically disposed transverse webs 11 are 110

integrally formed therewith and also with the front wall 5 of the manifold body. The upper ends of each web 11, which terminates at the approximate center of the manifold, 5 are integral with the cylindrical wall of an exhaust port 12. The intermediate exhaust ports 12 are spaced from each other and disposed at approximately equal distances from the center of the manifold.

- 10 13 designates the two intake ports of the manifold which are located between the intermediate exhaust ports 12 and the terminal exhaust ports 8. Obliquely inclined transversely disposed webs 14 and 15 respectively 15 are integrally formed with the top wall 6 of the manifold and with the wall of the exhaust port 12, said webs being connected to each other by the integral, substantially semi-circular wall 16, which extends around 20 the outer side of the intake port 13. 17 25 designates a rear side wall of the manifold which is integral with the top and bottom walls, the webs 11, 14 and 15, and the port walls 16, whereby the rear side of the manifold body between the several ports 12 and 16 is entirely closed. The remaining longitudinal portion of the manifold body at the rear side thereof, between the webs 11 and the terminal exhaust ports 8, is open as is 30 clearly shown in Fig. 3 of the drawings. Within the body of the manifold, between the spaced vertical webs 11 thereof, integrally connected transverse baffle plates 18 are arranged, said baffle plates extending 35 transversely between the front wall 5 and the rear side wall 17 of the manifold. These baffle plates are curved in relatively opposite directions in concentric relation to the respective exhaust ports 12 and the integrally 40 connected upper ends of these baffle plates terminate in a plane in which lie the axes of said ports. The lower ends of the baffle plates 18 are disposed in spaced relation to the respective webs 11 and at a point substantially midway between said webs in the 45 wall of the carburetor connection 10.
- The baffle plates 18 and the walls 9 in conjunction with the walls of the respective exhaust ports form curved upwardly extending 50 passages, designated 19, leading from a common inlet chamber 20 which receives the gaseous mixture. These passages above the baffle plates 18 communicate with passages, indicated at 21, which are formed by the 55 spaced webs 14 and 15. The downwardly curved central portions 9 of the wall 6, which are likewise concentrically related to the walls of the exhaust ports 12, constitute in effect continuations of the walls 14. Thus, 60 in effect, there is provided passages of uninterrupted continuity leading from the common gas inlet chamber 20 around the exhaust ports to the respective intake ports 13 of the manifold structure.
- 65 The top wall 6 of the manifold is pref-

erably provided at a point intermediate the spaced exhaust ports 12 and the intake ports 13 with the priming cups 22, through the medium of which gasoline or other similar refined hydrocarbon fuel may be initially 70 supplied to the engine cylinders for the purpose of quickly starting the motor when cold. After the engine has been started, the operation thereof may be continued by the use of kerosene or other relatively low grade 75 fuel, as will be presently more fully related.

Each of the integral wall connections between the webs 15 and the walls of the exhaust ports 12 is transversely bored to provide an opening 23 therein and additional 80 openings 24 are likewise formed in the front wall 5 of the manifold body between the terminal exhaust ports 8 and the intake port 16 for the purpose of receiving the usual 85 fastening bolts.

In assembling the improved intake manifold in operative position upon the Ford type of motor vehicle engine, the usual intake manifold is removed and my improved manifold is interposed between the exhaust manifold and the engine cylinder head, it being understood that the several intake and exhaust ports of the manifold are disposed in registering relation with the corresponding ports of the cylinders. The connections 90 of the exhaust manifold indicated in the drawings at 25 are then engaged with the outer sides of the several exhaust ports 8 and 12 of my improved manifold. Bearing brackets, indicated at 26, are disposed between the exhaust port connections to the intake manifold, each of said brackets including a main body plate recessed at its opposite ends as at 27 to receive the clamping bolts 28. Bearing lugs 29 and 30 are 100 formed upon the central portion of this plate and project respectively from the opposite side faces thereof. The lug 29 engages against the outer side wall 5 of the intake manifold. 31 designates the clamping members as are provided in the type of engine above referred to for holding the manifolds in their operative positions. One end of the clamping member is engaged against the lug 30, while the other end thereof bears 110 upon one of the exhaust manifold connections. By then tightening the nuts on the outer ends of the rods or bolts 28, the exhaust manifold will be securely clamped and held in operative relation to my improved intake manifold to receive the exhaust gases which pass through the several 115 exhaust ports 8 and 12.

In the operation of the invention, it will be understood that the gaseous fuel mixture 125 is drawn in the suction stroke of the engine pistons through the carburetor connection 10 into the inlet chamber 20. At this point the mixture strikes against the convex faces of the curved baffle plates 18 and is directed 130

laterally against the webs 11. It then passes upwardly and inwardly between the walls of the exhaust ports 12 and the baffle plates 18 and around the exhaust port walls 5 through the passages 21 to the intake ports 13. The flame and exhaust gases which enter the exhaust manifold 25 through the ports 12, heat the annular walls of said ports to a very high degree. The gaseous 10 mixture in its travel through the passages 19 is confined by the baffle plates 18 and forced to travel through said passages in close contact with the exhaust port walls. Thus it will be manifest that the mixture 15 is very highly heated and all solid particles of fuel which may be contained therein will be thoroughly vaporized. In the passage of the vaporized mixture into the passages 21, an equal division of the mixture will 20 be maintained owing to the fact that the top of the manifold is provided with the curved wall sections 9 which are concentric to the walls of the exhaust ports, effecting a division of the mixture above the upper 25 ends of the baffle walls 18 so that it will be delivered in uniform volume to the respective intake ports 13.

From the foregoing description, taken in connection with the accompanying drawings, the construction, manner of operation and several advantages of my invention will be clearly and fully understood. The improved intake manifold may be produced in the form of a single integral casting and 35 can therefore be expeditiously manufactured at relatively small cost. The manifold, as a whole, is of very simple construction, and while I have herein referred to the device as particularly designed for use in connection with the Ford type of motor vehicle engine, it will be at once apparent to one familiar with the art that by resorting to minor structural modifications, the manifold may also be adapted for use in connection 40 with various other types of such engines. In practice it has been found that the device accomplishes the intended purpose in a very satisfactory manner, and enables the engine to be operated on relatively low 45 grade hydrocarbon fuels, or with the more refined fuels, such as gasolene, with a material reduction in the consumption of the latter, though without impairing the power efficiency of the engine. As the low grade 50 fuels are procurable at considerably less cost than refined hydrocarbon fuels, the economy resulting from the use of the device will be at once manifest. The construction and relative proportions of the several parts of 55 the manifold, as indicated in the accompanying drawings, I have found to be productive of the best results. It is, however, to be understood that the several structural features of the device are susceptible of numerous 60 modifications, and I accordingly re-

serve the privilege of adopting all such legitimate changes therein, as may be fairly embodied within the spirit and scope of the invention as claimed.

Having thus fully described the invention, 70 what I desire to claim and secure by Letters Patent is:—

1. A manifold for internal combustion engines comprising a body having spaced non-communicating ports extending transversely 75 therethrough to receive the exhaust from the respective engine cylinders, said body being also provided with a fuel inlet chamber and intake ports disposed in spaced relation to the exhaust ports, and means for directing 80 the fuel mixture from the inlet chamber around the walls of the respective exhaust ports to the intake ports.

2. A manifold for internal combustion engines comprising a body having spaced non-communicating ports extending transversely 85 therethrough to receive the exhaust from the respective engine cylinders, said body being also provided with a fuel inlet chamber and intake ports disposed in spaced relation to 90 the exhaust ports, and a transversely disposed wall having portions disposed in concentric relation to the walls of the respective exhaust ports to direct the fuel mixture from the inlet chamber around the latter walls in 95 close contact therewith to the intake ports.

3. A manifold for internal combustion engines comprising a body having spaced non-communicating exhaust ports extending transversely therethrough to receive the exhaust from the respective engine cylinders, and an intake port disposed in spaced relation to each of the exhaust ports, said manifold body having a fuel inlet chamber and integrally connected walls defining passages leading from the inlet chamber around 100 the respective exhaust ports to the intake ports.

4. A manifold for internal combustion engines comprising a body having a fuel 110 inlet chamber, and integrally connected walls defining spaced intake and exhaust ports and a fuel receiving passage leading to the intake port, and a transverse wall constituting an integral part of the manifold 115 structure and disposed in spaced relation to the wall of the exhaust port to direct the fuel mixture around said port wall and in close contact therewith into said passage.

5. A manifold for internal combustion 120 engines comprising a body having a fuel inlet chamber, and spaced transversely extending walls at the upper side of said chamber defining exhaust ports, said manifold body also having additional transverse 125 walls defining intake ports laterally spaced from the respective exhaust ports and passages leading to said intake ports, and baffle walls extending transversely through the fuel inlet chamber and acting to direct 130

the gas mixture in equal volume around the walls of the respective exhaust ports and into said passages.

6. A manifold for internal combustion engines comprising a single structural unit and including a front side wall, top and bottom walls, and a plurality of integrally connected transverse walls defining intake and exhaust ports and a common fuel inlet chamber, and passages connecting the inlet chamber to the intake ports around said exhaust ports, a rear wall closing said chamber and the passages, said exhaust ports opening through the front and rear walls of the manifold and said intake ports opening through the rear wall thereof.

7. A manifold for internal combustion engines comprising a single structural unit and having an elongated body including a front wall and top and bottom walls, and terminal exhaust ports at the ends of the manifold body, the manifold structure also including integrally connected transverse walls between the top and bottom walls thereof and defining a plurality of intake and exhaust ports and a common fuel inlet chamber, and passages leading from said chamber to the respective intake ports, a rear wall closing the inlet chamber and said

passages, the exhaust ports opening through the front and rear walls of the manifold and the intake ports opening through the rear wall thereof.

8. In combination with an internal combustion engine having an exhaust manifold, an intake manifold comprising a single structural unit adapted to be interposed between the exhaust manifold and the engine cylinders and having a plurality of transverse walls defining intake and exhaust ports and a common fuel inlet chamber, the manifold structure being further provided with additional terminal exhaust ports, said exhaust ports of the intake manifold being open at their opposite ends and adapted to be connected to the exhaust ports of the engine cylinders and the respective fuel inlets of said exhaust manifold, the intake ports of said intake manifold opening upon one side of the manifold body and adapted for connection to the intake ports of the engine cylinders.

In testimony whereof I affix my signature in the presence of two witnesses.

FRANKLIN E. ARNDT.
